UNITED STATES PATENT OFFICE.

HAROLD VANDERHOOF, OF SAN FRANCISCO, CALIFORNIA.

VACUUM APPARATUS.

1,220,297.

Specification of Letters Patent. Patented Mar. 27, 1917.

Application filed June 3, 1916. Serial No. 101,516.

To all whom it may concern:

Be it known that I, HAROLD VANDERHOOF, a citizen of the United States, residing at No. 1283 Forty-second avenue, San Francisco, in the county of San Francisco and State of California, have invented certain new and useful Improvements in Vacuum Apparatus, of which the following is a specification.

10 This invention, relates to a vacuum apparatus which is operated by an internal-combustion engine, the apparatus being designed more particularly for attachment to the engine of a motor vehicle so that the body, 15 seats and other parts of the car may be easily cleaned. The pumping action of the engine is utilized to create the vacuum, and the apparatus is so constructed and arranged that it can be readily applied to the engine 20 without any changes in the structure thereof, and without affecting the ordinary operation of the engine.

In order that the invention may be better understood, reference is had to the accompanying drawing in which—

Figure 1 is an elevation showing the application of the invention, and Fig. 2 is a central vertical section of the dust strainer or separator.

30 Referring specifically to the drawing, 5 denotes an automobile or other motor vehicle having an ordinary multiple-cylinder, internal-combustion engine 6 provided with an intake manifold 7 through which the fuel-charges are conveyed to the engine cylinders from a carbureter 8. These parts are all constructed and arranged in the ordinary manner in view of which a further description thereof is deemed unnecessary. As is 35 well known, the engine 6, when running, creates a suction in the manifold 7, and this action is utilized for the operation of the present apparatus, which will now be described.

40 On the dash 9 of the car, is mounted a cylindrical or other suitable casing 10 closed at one end by a removable screw cap 11, and having attached to its other end a valve 12, the casing of which latter opens at one end 45 into the casing 10, and has connected to its other end a tubing 13 leading to and having a connection with the intake manifold 7 at any convenient point between the carbureter 8 and the cylinder inlet ports. In the casing 50 10, over the end of the valve casing opening thereinto, is mounted a fine-mesh screen 14.

The tubing 13 opens into the manifold 7, and hence, when the engine 6 is running, the suction created in said manifold will withdraw air from the casing 10, thus producing 60 a partial vacuum therein.

On the cap 11 is a nipple 15 for making connection with a flexible hose 16 of suitable length provided with an ordinary suction nozzle 17 such as is used in vacuum cleaning 65 apparatus.

The casing 10 contains a fabric strainer bag 18 having its mouth located opposite the nipple 15, so that the dust-laden air entering through the nipple passes into the bag, and in passing through the meshes thereof, the air is strained, the dust particles remaining in the bag. The bag seats in a cylindrical screen 19 open at one end to receive the bag, the other end being closed and imperforate, 70 as indicated at 20, this end being opposite and adjacent to the screen 14 so that the suction is thrown to the sides of the bag. The bag is removably mounted in the casing 75 so that it may be taken out and relieved of 80 its contents, after taking off the cap.

The upper end of the screen 19 is soldered or otherwise rigidly fastened in a sleeve 21 fitting snugly in the upper end of the casing 10 and resting at its lower end on an annular shoulder 22 inside the latter. The bag 18 is carried by a ring 23 to which it is sewed or otherwise made fast at its mouth. When the parts 18, 19 and 21 are positioned in the casing 10, the sleeve 21 rests on the shoulder 22, and the ring 23 seats on the top edge of the sleeve 21, the ring being so positioned that when the cap 11 is screwed down it presses the mouth of the bag, reinforced by the ring, down on the top edge of the sleeve, this portion of the bag therefore acting as a washer, so that the cap 11 is sealed air-tight.

The apparatus can be cut off from the engine by closing the valve 12.

It will be seen that the invention provides a handy and convenient automobile accessory for the purpose stated, and it can be easily applied, without any change in the structure of the car or its engine, and without affecting the ordinary operation of the engine.

The device also operates to save gasolene when the engine is running, by introducing an additional volume of clean filtered air into the fuel mixture as it passes through the manifold 7 to the engine cylinders. This

additional air supply results in a more thorough vaporization of the fuel, and has in actual practice been found to reduce the amount of fuel required, and also to add to 5 the speed of the car.

I claim:

The combination with an internal-combustion engine and its intake manifold; of an air suction pipe connected to the intake 10 manifold between the carbureter and the fuel inlets of the engine, anteriorly of the

carbureter, a strainer chamber having an air inlet and an air outlet, the air outlet being connected to the aforesaid suction pipe, and a valve in the suction pipe.

15

In testimony whereof I affix my signature in the presence of two witnesses.

HAROLD VANDERHOOF.
